(57) **ABSTRACT**

A lubricant circuit of a camshaft adjuster is provided. In conventional camshaft adjusters, lubricant is supplied from a cylinder head to the camshaft adjuster via a supply channel (66) and a receiving channel (69), with an annular groove that encircles in a circumferential direction being located between the supply channel and the receiving channel in order to ensure a continuous lubricant supply. According to the invention, the lubricant is transferred from the supply channel to the receiving channel in a discontinuous manner. The omission of the encircling annular groove causes a discontinuous or cyclic flow of lubricant so that lubricant is transferred only when the supply channel (66) is at least partially aligned with the receiving channel (69).

CAMSHAFT ADJUSTER

BACKGROUND

The invention relates to a camshaft adjuster for an internal combustion engine, in which lubrication is performed by a lubricant flow.

Camshaft adjusters can be roughly classified as follows:

A. Phase adjusters with a control element, that is, a functional unit, which joins in the mass flow or energy flow formed, for example, hydraulically, electrically, or mechanically and rotates with gear elements of the camshaft adjuster.

B. Phase adjusters with a separate setting element, that is, a functional unit, in which the control parameter required for the control method of the control element is formed from the controller output parameter, and a separate control element. Here, there are the following structural forms:

a. Phase adjusters with a co-rotating actuator and a co-rotating control element, for example, a step-up ratio gear, whose adjustment shaft can be advanced by a co-rotating hydraulic motor or centrifugal force motor and can be reset by a spring.

b. Phase adjusters with a co-rotating control element and a stationary, engine-fixed actuator, for example, an electric motor or an electrical or mechanical brake, see also DE 100 38 354 A1, DE 102 05 034 A1, EP 1 043 482 B1.

c. Phase adjusters with a direction-dependent combination of solutions according to a. and b., for example, an engine-fixed brake, in which part of the brake power is used for adjustments toward an advanced position, in order to tension a spring, which allows resetting after the brake is deactivated, see also DE 102 24 446 A1, WO 03-098010, US 2003 0226534, DE 103 17 607 A1.

In systems according to B.a. to B.c., actuators and control elements are connected to each other by an adjustment shaft. The connection can be switchable or non-switchable, detachable or non-detachable, lash-free or with lash, and flexible or stiff. Independent of the structural form, the adjustment energy can be realized in the form of supply through a drive output and/or brake output, as well as with the use of leakage power of the shaft system (e.g., friction) and/or inertia and/or centrifugal force. Braking, advantageously in the adjustment direction of "retarded" can also be realized under the full use or shared use of the friction power of the camshaft. A camshaft adjuster can be equipped with or without mechanical limiting of the adjustment range. As a gear in a camshaft adjuster, one-stage or multiple-stage triple-shaft gears and/or multiple links or coupling gears are used, for example, in structural form as a wobble-plate gear, eccentric gear, planetary gear, undulating gear, cam-plate gear, multiple-link or linked gear, or combinations of the individual structural forms in a multiple-stage construction.

For operation of the camshaft adjuster, a lubricant must be fed to lubricating positions, especially bearing positions and/or rolling toothed sections, wherein the lubricant is used for lubricating and/or cooling components of the camshaft adjuster that can move relative to each other. For this purpose, the camshaft adjuster has a lubricant circuit, which can be coupled, for example, with the lubricant circuit of the internal combustion engine.

From DE 102 48 355 A1, it is known to feed lubricant to a camshaft via a camshaft bearing. For this purpose, the cylinder head or the camshaft bearing has a supply channel oriented in the radial direction to the camshaft. A receiving channel (here also oriented in the radial direction) is arranged aligned with the supply channel in the camshaft and moves relative to the supply channel. In the region of the receiving

2

channel, the camshaft has a peripheral groove in the circumferential direction, which guarantees that the transfer of lubricant from the supply channel to the receiving channel is continuous and is possible for every angle position of the camshaft, wherein the lubricant is led from the supply channel via the groove to the receiving channel.

SUMMARY

10 The present invention is based on the objective of enabling an improved supply of lubricant to the camshaft adjuster and/or

an improved installation space construction of a supply region for the lubricant.

15 This objective is met according to the invention.

The invention first does away with the preconception that a supply of lubricant is necessary for each angular position of the camshaft and thus a continuous lubricant supply is required. Instead, the invention uses discontinuous lubricant supply.

20 Such a discontinuous lubricant supply can be created in a simply way according to the invention, under some circumstances, without requiring an especially complex control or regulation unit, an actuator, or a valve. According to the invention, the lubricant supply is enabled or shut off in a motion-controlled way by the relative motion of the components of the camshaft adjuster, which include the supply channel and the receiving channel.

25 The solutions known from the state of the art require a ring groove in the casing surface of the camshaft or in the cylinder head or the camshaft bearing, wherein, due to the groove, a width of the camshaft bearing or a counter surface of the cylinder head requires an enlarged construction. Such additional installation-space conditions can be avoided according to the invention.

30 According to the invention, lubricant is transmitted only when the supply channel and receiving channel are approximately aligned with each other. In addition, leakage with reduced transport volume can lead to transmission. In addition, in the scope of the invention, a groove not completely encircling the peripheral surface can be provided in the region of the supply channel and/or receiving channel, by which the period of lubricant transmission is lengthened. In the course of the relative motion between the supply channel and receiving channel, a transfer cross section that increases with time can be formed, which falls to zero again after reaching a maximum (aligned boreholes), by which the time period of the transfer volume flow can be set. Optionally, the width of a groove that is not completely encircling in the circumferential direction can be constructed suitably for influencing the time period of the transfer volume flow.

35 Due to the measures according to the invention, the transport quantity of the lubricant can be reduced relative to a continuous lubricant supply. Furthermore, pulses of the lubricant flow are generated in the camshaft adjuster, which can lead to improved lubrication and improved distribution of the lubricant.

40 The construction according to the invention is not limited to embodiments according to the state of the art named above, in which the supply is realized via a camshaft bearing. Instead, for creating a discontinuous lubricant flow, the supply channel and receiving channel can be arranged in any components, which are moved relative to each other in the course of the rotation of the camshaft and/or the camshaft adjuster.

45 For the case that the transfer of lubricant through a single supply channel and receiving channel is not sufficient, several

supply channels and/or receiving channels could be distributed uniformly or non-uniformly around the periphery.

If undesired pulse oscillations are produced in the lubricant circuit, at least one non-return valve could be arranged in the lubricant circuit, in particular, in the region of the camshaft adjuster, the camshaft, the camshaft bearing, or the cylinder head.

According to another construction of the invention, the pulses of the lubricant are used in such a way that downstream of the receiving channel there is a lubricant injection nozzle, from which, with increasing pressure for the opened transfer cross section, the lubricant can be discharged with increasing velocity.

Advantageous improvements of the invention emerge from the claims, the description, and the drawings. The advantages named in the introduction of the description for features and combinations of several features are merely exemplary, without these having to be necessarily realized by embodiments according to the invention. Additional features are to be taken from the drawings—in particular, the illustrated geometries and the relative dimensions of several components to each other, as well as their relative arrangement and effective connection. The combination of features of different embodiments of the invention or of features of different claims is similarly possible deviating from the selected associations of the claims and is suggested with this reference. This also relates to features that are shown in separate drawings or are noted in the associated description. These features can also be combined with features of different claims. Likewise, features listed in the claims can be left out for other embodiments of the invention.

BRIEF DESCRIPTION OF THE DRAWINGS

Additional features of the invention emerge from the following description and the associated drawings, in which embodiments of the invention are shown schematically. Shown are:

FIG. 1 a schematic diagram of a camshaft adjuster,

FIG. 2 a schematic diagram of a camshaft adjuster with a wobble-plate gear,

FIG. 3 a schematic diagram of a camshaft adjuster with a lubricant circuit,

FIG. 4 a schematic diagram of a camshaft adjuster with a lubricant circuit, in which a filter element is integrated,

FIG. 5 a half-longitudinal cross-sectional view of a camshaft adjuster with a dead space for the deposition of contaminant particles,

FIG. 6 a schematic diagram of a camshaft adjuster with a lubricant circuit, which is equipped both on the input side and also on the output side with a throttle and a diaphragm,

FIG. 7 a longitudinal cross-sectional view of a camshaft adjuster with guidance of the lubricant into a flow channel,

FIG. 8 a longitudinal cross-sectional view of a camshaft adjuster in which two diaphragms are connected one after the other in a flow channel,

FIG. 9 a longitudinal cross-sectional view of a camshaft adjuster with a flow element, which is set on a central screw and which forms a diaphragm with an inner casing surface of the camshaft,

FIG. 10 a longitudinal cross-sectional view of a camshaft adjuster with a diaphragm formed between a hollow shaft and a central screw,

FIG. 11 a longitudinal cross-sectional view of a camshaft adjuster with the feeding of a lubricant via a transfer cross section from an outlet opening of the cylinder head to an inlet cross section of the camshaft,

FIG. 12 a longitudinal cross-sectional view of another construction of a lubricant feed to a camshaft and to a camshaft adjuster,

FIG. 13 a longitudinal cross-sectional view of another construction of a lubricant feed to a camshaft and to a camshaft adjuster,

FIG. 14 a longitudinal cross-sectional view of another construction of a lubricant feed to a camshaft and to a camshaft adjuster,

FIG. 15 a longitudinal cross-sectional view of another construction of a lubricant feed to a camshaft and to a camshaft adjuster,

FIG. 16 a longitudinal cross-sectional view of a camshaft adjuster with different examples for an arrangement of diaphragms or throttles for influencing the flow of a lubricant,

FIG. 17 a perspective view of a camshaft adjuster with openings of a housing of the gear for passage of the lubricant in the form of droplets, lubricant mist, or sprayed lubricant,

FIG. 18 another perspective view of the camshaft adjuster according to FIG. 17 with other options for openings,

FIG. 19 a view of a camshaft adjuster in the installed state with options for lubrication via droplets, a lubricant mist, and/or sprayed lubricant, and

FIG. 20 a view of a camshaft adjuster in the installed state in side view with a drop plate, on which droplets of an oil mist settle and drop in the direction of the interior of the camshaft adjuster.

DETAILED DESCRIPTION OF THE PREFERRED EMBODIMENTS

In the figures, components that correspond with respect to form and/or function are to some extent provided with the same reference symbols.

FIG. 1 shows in a schematic diagram a camshaft adjuster 1, in which, in a gear drive 2, the movement of two input elements, here a drive wheel 3 and an adjustment shaft 4 (also called wobble plate), is superimposed on an output movement of an output element, here a driven shaft 5 locked in rotation with a camshaft or the camshaft 6 directly. The drive wheel 3 is in driven connection with a crankshaft of the internal combustion engine, for example, via a traction element, such as a chain or a belt, or a suitable toothed section, wherein the drive wheel 3 can be formed as a chain or belt wheel.

The adjustment shaft 4 is driven by an electric motor 7 or is in active connection with a brake. The electric motor 7 is supported relative to the surroundings, for example, the cylinder head 8 or another engine-fixed part.

FIG. 2 shows an example construction of a camshaft adjuster 1 with a gear drive 2 in a wobble-plate construction. A housing 9 is locked in rotation with the drive wheel 3 and is sealed in an axial end region by a sealing element 10 relative to the adjustment shaft 4. In the opposite axial end region, the housing 9 is sealed with a sealing element 11 relative to the cylinder head 8. An end region of the camshaft 6 projects into an inner space 36 formed by the housing 9 and the cylinder head 8. Arranged in the inner space are furthermore, an eccentric shaft 13 connected via a coupling 12 to the adjustment shaft 4, a wobble plate 15 supported by a bearing element 14, for example, a roller bearing, and a hollow shaft 16, which is supported by a bearing element 17, for example, a roller bearing, on the inside in a central recess of the eccentric shaft 13 and carries a driven conical gear wheel 18. The driven conical gear wheel 18 is supported by a bearing 19 relative to the housing 9. In the interior, the housing 9 forms a drive conical gear wheel 20. The wobble plate 15 has suitable toothed sections on opposite end faces. The eccentric shaft 13

with the bearing element 14 and wobble plate rotates about an axis inclined relative to a longitudinal axis 21-21, so that the wobble plate meshes on sub-regions offset in the peripheral direction relative to each other, on one hand, with the drive conical gear wheel 20 and, on the other hand, with the driven conical gear wheel 18, wherein a step-up or step-down ratio is given between the drive conical gear wheel and driven conical gear wheel. The driven conical gear wheel 18 is locked in rotation with the camshaft 6.

For the embodiment shown in FIG. 2, the hollow shaft 16 with the driven conical gear wheel 18 is connected via a central screw 22, which extends through the hollow shaft 16, to the camshaft 6 on the end. Lubrication with a lubricant, especially oil, is necessary in the region of the lubricating positions 23, 24, which can involve, for example,

the contact surfaces between the drive conical gear wheel 20 and wobble plate 15,

the contact surface between the wobble plate 15 and driven conical gear wheel 18,

bearing 19,

bearing element 14, and/or

bearing element 17.

Here, a continuous, cyclical, pulsing, or intermittent feed and/or forwarding of a lubricant via the lubricant channels is realized. Using a feed recess 25 of the cylinder head 8, the lubricant is fed to a flow channel 26 of the camshaft 6, which communicates with a flow channel 27, which is formed with a hollow cylindrical shape between an inner casing surface 28 of the hollow shaft 16 and an outer casing surface 29 of the central screw 22. Through the use of radial boreholes 30 of the hollow shaft 16, the lubricant can emerge from the flow channel 27 outwardly in the radial direction and can be fed to the lubricating positions.

FIG. 3 shows a schematic lubricant circuit. The lubricant is fed from a reservoir 31, for example, an oil pan or an oil tank, via a pump 32, for example, a motor-oil pump, through a filter 33, in particular, a motor-oil filter, to the supply recess 25 and the flow channel 26 of the camshaft 6. The lubricant leaves the camshaft adjuster 1 or the housing 9 of the camshaft adjuster via an outlet opening 34 and is fed back into the reservoir 31.

In contrast to the embodiment according to FIG. 3, the schematic lubricant circuit according to FIG. 4 has an additional filter element 35. The filter element 35 is advantageously allocated to the camshaft adjuster 1 and is arranged, for example, after a branch of the lubricant circuit to other components to be lubricated and allocated exclusively to the branch of the lubricant circuit that is used for lubricating the camshaft adjuster. Here, the filter element 35 is arranged as close as possible to the installation position of the camshaft adjuster 1 or in the camshaft adjuster itself. The filter element 35 can be used to keep processing residue in the flow channels, which are arranged upstream of the filter element 35, away from the flow channels of the cylinder head and the camshaft. Furthermore, fabrication residue and contaminant particles in the lubricant can be kept away from the gear drive 2 of the camshaft adjuster 1. Furthermore, a diaphragm characteristic or a throttle effect of the filter element 35 can be used selectively, in order to influence the pressure, the volume flow, and the velocity of the lubricant. The filter element 35 is advantageously to be implemented in such a way that it cannot become blocked or clogged due to the flow relationships at the maximum contamination to be expected with particles and contaminants during the runtime of the camshaft adjuster. For example, the arrangement in a rising line and/or as a secondary current filter is advantageous.

The filter element 35 can be constructed, e.g., as a screen,

5 a ring filter,
a plug-in filter,
a shell filter,
filter plates,
filter net, or
sintered filter.

According to FIG. 5, lubricant is fed into an inner space 36 of the housing 9, for example, according to the embodiments described above, wherein, in the inner space 36, the lubricant 10 comes into contact with the lubricating positions. The inner space 36 is in a lubricant path connection with a dead space 37, which is arranged at a position of the inner space 36 farthest removed in the radial direction. A connection of the dead space 37 to the inner space 36 can be formed over a large 15 surface via transfer cross sections or via separate channels, by which lubricant can be fed to and also discharged from the dead space 37.

For the embodiment shown in FIG. 5, the dead space 37 is 20 constructed as a surrounding ring channel. A dead space 37 25 involves, in particular, a space, in which the lubricant moves with minimal velocity or is almost at rest, so that the dead space 37 is not arranged in a direct, maximum flow-through zone of the lubricant. In the dead space 37, due to the rotation 30 of the housing 9, the lubricant is exposed to a centrifugal force, by which heavy components and particles suspended in the lubricant are pressed outwardly and can be deposited on a wall 38 on the outside in the radial direction and are not led back to a lubricating position. It is further possible that the annular dead space 37 is separated in the peripheral direction 35 by intermediate walls, so that, in the peripheral direction, several individual chambers are formed, by which it is avoided that in the dead space 37, the lubricant can move in the peripheral direction relative to the housing 9. Settling of contaminants is thus realized analogous to a rotating centrifuge.

Dead spaces according to the dead space 37 can be 40 arranged at any position in the gear drive, as well as in the region of the camshaft, by which it can be achieved that important functional surfaces, for example, in the direct neighborhood of the dead spaces, are not "silted up" due to 45 centrifuged contaminants in the gear. The centrifugal effect is amplified by an increase in the distance of the dead spaces from the longitudinal axis 21-21.

According to a first construction, the dead space has no 45 additional outflow, so that centrifuged contaminant particles are deposited permanently in the dead space 37. According to the preferred construction shown in FIG. 5, the dead space has 50 at least one additional outlet opening 39, 40, wherein the outlet opening 39 is oriented in the axial direction and the outlet opening 40 is oriented in the radial direction. Due to the 55 radial centrifugal force and/or the pressure ratios in the dead space 37 in comparison with the surroundings of the camshaft adjuster 1, the lubricant with deposited contaminant particles moves in the radial direction out of the outlet opening 40, wherein the feeding of the contaminant particles is supported 60 by the centrifugal effect. Alternatively, feeding through the outlet opening 39 is realized exclusively through the pressure difference in the dead space 37 on one side and in the surroundings of the camshaft adjuster 1 on the other side.

For an alternative construction, contaminants are separated 65 in such a way that the lubricant is guided in a flow channel with a labyrinth-like or zigzag-shape construction. Contaminant separation through such a labyrinth-like contaminant separator touches upon the different inertia of the lubricant and interfering particles in the lubricant. In particular, for high flow rates, a strong deflection of the lubricant flow can lead to the result that the particles are not deflected, but

instead are deposited at the borders of the labyrinth. For the case that individual channels of the labyrinth are oriented in the radial direction, deposition in the labyrinth on surfaces on the outside in the radial direction can take place in such channels, as well as similarly in axial channels, due to the centrifugal force described above. An alternative or additional separating effect can be produced when the lubricant is decelerated and accelerated, wherein the lighter lubricant can be accelerated more easily, while contaminant particles remain behind.

In addition to generating the centrifugal effect due to rotation of the housing 9 or other parts of the camshaft adjuster 1, the centrifugal effect can be generated at least partially in such a way that the flow channels guiding the lubricant are oriented in a circular or spiral construction, so that a deposit can form on the outer boundaries of the flow channels just due to the movement of the lubricant through the curved flow channels.

Deviating from the embodiments shown in FIGS. 3 and 4 for a lubricant circuit, the schematic lubricant circuit shown in FIG. 6 has an input-side diaphragm 41 and also an input-side throttle 42 and an output-side diaphragm 43 and also an output-side throttle 44. The diaphragms 41, 43 and throttles 42, 44 form flow elements for influencing the flow ratios in the lubricant circuit. The flow elements named above are allocated to a parallel lubricant path, which applies a force exclusively to the camshaft adjuster 1. Advantageously, the flow elements are arranged close to the camshaft adjuster 1 or are integrated at least partially into the adjuster, the camshaft, or a cylinder head in the region of a bearing position for the camshaft.

Through the use of the diaphragms 41, 43 and throttles 42, 44, the volume flow to the camshaft adjuster is throttled. Additional throttling can be produced through the use of the filter element 35. Advantageously, the filter element is arranged in the flow direction upstream of the flow elements, so that the flow elements do not become blocked by particles or clogged over the course of time.

In addition to the use of flow elements with constant flow characteristics, a flow element that is continuous or that can be changed in steps can be used. The use of a flow element, whose flow effect is variable

as a function of an engine rotational speed,
coupled with a feeding volume of the pump 32, and/or
as a function of the temperature of the camshaft adjuster 1

or the lubricant

is possible, wherein the mentioned changes can be generated automatically in a mechanical way or by a suitable control or regulating device, which acts on the flow element.

The flow element is changed in such a way that, for example, the volume flow of the lubricant is held at a constant value independent of the temperature of the lubricant. It is also possible that the volume flow is increased or decreased due to an effect of the flow element in operating regions, in which there are higher or lower lubricant or cooling requirements.

For the construction of the flow elements in the form of throttles 42, 44 and diaphragms 41, 43, under some circumstances, embodiments are to be used, in which ring gaps or annular cross sections are used instead of boreholes with, for example, a circular cross sectional surface, because, under some circumstances, a borehole can be more easily blocked than a ring gap.

For the embodiment shown in FIG. 7, lubricant is fed via several boreholes or receiving channels 45 of the camshaft 6, wherein the receiving channels 45 are inclined relative to the longitudinal axis 21-21 and the radial orientation. The cam-

shaft 6 has an end-face blind borehole 46, which transfers with a conical chamfer 47 into a thread for receiving the central screw 22. The receiving channels 45 open into the chamfer 47. In the end region opposite the chamfer 47, the receiving channels 45 are fed with lubricant from a supply groove of the cylinder head 8. A groove 48 surrounding in the radial direction is formed with the rectangular geometry shown in the longitudinal section approximately in the center in the receiving channel 45.

One part of the lubricant fed to the groove 48 via the receiving channel 45 and borehole 46 is led via an axial borehole 49 of the camshaft 6, which opens into the groove 48, and an axial borehole 50 of the housing 9 with a certain amount of overlap, but offset in the radial direction, in the inner space of the gear 2 to the lubricating positions, for example, to the bearing element 17, the bearing element 14, the rolling toothed connections of the wobble plate 15, and/or the bearing 19.

The other part of the lubricant fed to the groove 48 is led via a flow channel 51 with a circular ring-shaped cross section and formed between the inner casing surface of the hollow shaft 16 and the outer casing surface of the central screw 22 to at least one radial borehole 52 to a lubricating position, for example, the bearing position 17 or in the inner space of the gear 2. The groove 48 is constructed with a radial projection, which extends over the borehole 49, so that a peripheral, ring-shaped dead space 37 is formed on the outside in the radial direction. Between the boreholes 49, 50, a transfer region 53 can be formed in the shape of a recess, a radial groove, or the like, in order to allow transfer between the boreholes 49, 50 that are offset relative to each other in the radial direction. In the form of the boreholes 49, 50 that are not aligned with each other, for a partial overlap of the boreholes, a kind of diaphragm can be formed with a small transfer cross section or diaphragm cross section, although the boreholes 49, 50 can be produced with relatively large diameters and thus with rough tools.

For a construction that otherwise corresponds to FIG. 7, for the embodiment shown in FIG. 8, the extent of the hollow shaft 16 in the longitudinal direction lengthens in such a way that the hollow shaft projects into the groove 48. A diaphragm for transfer of lubricant from the borehole 46 to the groove 48 is formed between a peripheral edge 54, which is formed by the inner casing surface of the borehole 46 and also a transverse surface 55 defining the groove, and an edge 56, which is formed by the outer casing surface 57 of the hollow shaft 16 and an end face 58 of the hollow shaft 16.

For a construction that otherwise corresponds to the embodiments described above, the camshaft 6 according to FIG. 9 has no groove 48. The boreholes 49, 50 and the transfer region 53 are also not provided for the embodiment according to FIG. 9, so that the lubricant is fed from the borehole 46 completely to the flow channel 51. In the circular ring-shaped flow channel, which is formed in the borehole 46 and which has a rectangular half cross section and which is defined on the inside in the radial direction by the casing surface of the central screw 22 and also by an end face 58 of the hollow shaft 16, there is a flow element 59, which can involve a ring made from, for example, plastic or an elastomer, and covered by the central screw 22. For the embodiment shown in FIG. 9, the flow element 59 has an approximately T-shaped half longitudinal section, wherein the transverse leg of the T contacts the casing surface of the central screw 22 under elastic pressure on the inside in the radial direction, while the vertical leg of the T extends outward in the radial direction and the end face of this leg forms a ring gap 60 with the borehole 46, by which a diaphragm is created.

In a deviating construction, the flow element 59 can be tensioned outward, for example, in the radial direction against the borehole 46, wherein, in this case a ring gap 60 is formed between the inner surface of the flow element and the central screw. Also, a positive-fit holding of the flow element 59, for example, in a suitable groove of the camshaft or the central screw, is conceivable. An arbitrary construction of the contours of the flow element 59 in the region of the ring gap 60 is possible for influencing the flow ratios, for example, with stepped transitions or continuous transitions.

For the embodiment shown in FIG. 10, the hollow shaft 16 has in the region of the flow channel 51 a radial, peripheral groove 61, which is defined on the side facing the chamfer 47 by a peripheral, radial projection 62 pointing inward in the radial direction. Between the projection 62 and the casing surface of the central screw 22, a ring gap 63 is formed, which represents a diaphragm. The groove 61 forms a dead space 37 on the outside in the radial direction, because both the ring gap 63 and also the flow channel 51 open into the groove 61 on the inside in the radial direction from the dead space 37.

The camshaft 6 is supplied with a lubricant from a lubricant gallery of the cylinder head 8. The transition of the lubricant from the engine-fixed cylinder head 8 to the rotating camshaft 6 is realized usually by known rotation transmitters. This typically involves a ring groove 64 of the outer casing surface of the camshaft 6. The ring groove 64 is enclosed by a corresponding cylindrical casing surface 65 of the cylinder head 8, to which a pass borehole or supply channel 66 oriented in the axial direction toward the ring groove 64 leads out of the lubricant gallery. The supply channel 66 can pass through the casing surface 65, as shown in FIG. 11, in the radial direction or can pass through this surface, for example, tangentially.

A rotation transmitter can be arranged in a radial bearing for the camshaft 6 or on a separate shoulder. For the latter, however, due to the usually larger radial gap, often sealing rings 67, 68, for example, a steel sealing ring, cast-iron sealing ring, or plastic sealing ring, are required. In an arrangement of the rotation transmitter in a radial bearing of the camshaft 6 it is to be taken into account that the bearing width is reduced by the width of the ring groove.

In another embodiment, ring grooves can be constructed fixed to the cylinder head, for example, in the bearing, the bearing bridge, or an installed bearing bushing. In the camshaft, no ring grooves 64 are required.

The use of a rotation transmitter described above causes a continuous flow of lubricant from the cylinder head 8 into the camshaft 6 due to the peripheral ring groove and the radial boreholes or receiving channels 69, which connect the ring groove 64 to the borehole 46.

For a special construction, the supply channel 66 and the ring groove 64 are arranged offset relative to each other in the axial direction, by which, in the transfer of the lubricant from the supply channel 66 to the ring groove 64, a type of throttle is created, whose opening cross section becomes smaller the greater the offset in the axial direction between the supply channel 66 and ring groove 64. A throttle effect can also be achieved for a relatively large diameter of the supply channel 66 and a large width of the ring groove 64, so that no small boreholes or grooves, which are sensitive to contaminants and production, have to be created.

According to another special construction, lubricant is fed via a cyclical lubricant supply. In such a case, the ring groove 64 is left out, so that a lubricant connection between the supply channel 66 and the receiving channels 69 is given only for rotational positions of the camshaft 6, for which the channels 66, 69 align with each other or overlap. If increased transfer times are desired, then the transition region between

the supply channel 66 and receiving channel 69 of the cylinder head 8 or the casing surface of the camshaft 6 can have a groove running through a partial extent, so that a transfer from the supply channel 66 to the receiving channel 69 is possible as long as these channels 66, 69 are connected to each other by the groove. In addition, through the construction of the width profile of the groove, there can be a variable transfer of the lubricant. Thus, a volume flow and mass flow of the lubricant can be given structurally and cyclically. Furthermore, a pulsing lubricant flow can be realized, which results in fluctuations in pressure that can be used, for example, for better mixing and wetting of the lubricating positions with the lubricant. Furthermore, through pulsing lubricant flows, the risk of blockages can be reduced, for example, for diaphragms or throttles. If such lubricant pulses lead to pulse oscillations in the lubricant cycle, then a non-return valve can be arranged in the lubricant circuit, in particular, in the region of the cylinder head 8, in the region of the camshaft, and/or in the gear drive.

FIG. 12 shows an embodiment, in which lubricant is fed via a radial blind borehole or a supply channel 70, an axial, end-face blind borehole 71 of the camshaft opening into the supply channel 70, and a pass borehole 72 of the housing 9. Assembly is simplified when a peripheral ring groove 73 is provided in the transition region between the boreholes 71 of the camshaft and the boreholes 72 of the housing 9, by which, during assembly, the boreholes 71, 72 do not have to be aligned coaxial to each other.

FIG. 13 shows an embodiment, which corresponds essentially to the embodiment according to FIG. 9, wherein, however, no flow element 59 is provided.

FIG. 14 shows an embodiment, in which the ring groove 64 is connected directly to the ring channel 73 via a borehole or receiving channel 74 inclined relative to the longitudinal axis 21-21 and the transverse axis.

For the embodiment shown in FIG. 15, the direct connection of the ring channel 73 and the ring groove 64 is realized via a borehole 75, which is formed on the end face in the camshaft and which opens into the ring groove 64 and which is drilled through the ring channel 73.

In addition to the structural measures for constructing the flow cross sections in the cylinder head and also in the camshaft, the flow ratios in the lubricant circuit in the gear can be influenced. Here, the supply borehole can be throttled through the use of a throttle or diaphragm. Alternatively or additionally, the throttling of the discharge through a rear-side closing of the gear, for example, with a sheet-metal cover, is possible, which forms, together with the adjustment shaft, a ring-shaped gap, in particular, with a gap height in the range from 0.1 to 2 mm.

In addition, it is possible to use bearings in the gear drive, which are equipped with sealing elements. According to FIG. 16, a ring channel between the hollow shaft 16 and central screw 22 has a ring width in the range from 0.2 to 1 mm. The radial connection boreholes between this flow channel and the inner space of the gear advantageously have a diameter between 0.5 and 3 mm. Additional influences or throttles or diaphragms can be realized by setting the axial and/or radial gaps 76, which can be set structurally and which form flow cross sections or diaphragms or throttles for the lubricant.

According to another construction of a camshaft adjuster 1, the outer casing surface of the housing 9 has recesses or windows 77, which can be distributed uniformly or non-uniformly in the peripheral direction, cf. FIG. 17.

FIG. 18 shows additional options for the arrangement of recesses or openings 78 in the region of one end face of the camshaft adjuster 1. A transmission of the lubricant via the camshaft can be eliminated if a lubricant is fed through the

openings 78, 77 to the gear drive 2. For example, the lubricant can be fed via a lubricant injector through the openings 77, 78. Such a lubricant injector can be fixed to the cylinder head or arranged on a timing case. In the simplest case, a lubricant injector can involve only one lubricant borehole, from which a fine lubricant stream is discharged and which occurs at a point outside of the gear drive or within the gear drive, for example, through the openings 77, 78. In particular, such a point can lie as close as possible to the rotational axis in the interior of the gear. Due to the centrifugal force acting on the lubricant in the rotating system, the lubricant is distributed outward to the lubricating positions, for example, to a bearing and/or to the toothed section.

In addition, through the arrangement of the openings 77, 78 of the gear housing, the lubricant can be sprayed directly onto a toothed section or other lubricating positions. It is also conceivable that the spraying with lubricant is combined with the lubricant supply of other engine components, for example, a chain or a tensioner. It is also conceivable that a point or a surface outside of the gear drive 2 is sprayed with the lubricant. Lubrication is then guaranteed through the rebounding or deflected lubricant or a lubricant mist generated in this manner.

According to an alternative construction, a lubricant supply can be realized by the lubricant mist, which is already present in a timing case and which can penetrate into the camshaft adjuster through the openings 77, 78.

In another construction of a lubricant supply according to FIG. 20, outside of the gear there is a drop plate 80, on which the lubricant mist condenses and drips. Alternatively or additionally, special drop lubricant nozzles can be provided, which are oriented selectively in the direction of the openings 77, 78.

To reliably guarantee functioning for lubrication with a lubricant mist, mist lubricant droplets, or with a lubricant stream, even at low temperatures of the lubricant or for a cold start, the lubricating positions, for example, slide bearings and/or toothed sections, are to be equipped with emergency-running properties. Such emergency-running properties can be guaranteed, for example

by a coating of the functional partners or by forming lubricant reservoirs.

In particular, the lubricant reservoirs are provided by microscopically or macroscopically small pockets of the lubricating positions, in which lubricant can be stored for a cold start or for low lubricant temperatures. Better emergency-running properties can also be provided, advantageously, when roller bearings are provided at the bearing positions as much as possible.

Furthermore, for lubrication, oil dripping from an oiled traction element (timing chain) can also be used, which passed through an opening of the housing. Under some circumstances, the traction element is lubricated by wobble or spray oiling or by stripping oil from oiled chain tensioners or deflection rails. A part of the oil supplied by the chain can drop above the drive wheel (chain wheel) of the gear drive and can thus be led into openings of the gear drive lying underneath. In addition, it is possible to feed oil through the capillary effect to the gear drive or to drip positions lying above the gear drive. It is also possible that oil is "blown," for all practical purposes, to the lubricating position, by air currents resulting, e.g., from the drive movement of the control drive or adjustment parts.

The invention claimed is:

1. Camshaft adjuster for an internal combustion engine for maintaining and adjusting a relative angle position between a drive element and a driven element the camshaft adjuster comprising a gear drive connecting the drive element and the driven element and a lubrication circuit for lubrication of a

14

- functional surface of the gear drive, a lubricating point of the gear drive or a bearing point in a housing of the camshaft adjuster, the lubricant circuit feeds lubricant to the camshaft adjuster via a supply channel, which communicates with a receiving channel of the camshaft adjuster, and the receiving channel can move relative to the supply channel, and a transfer cross section between the supply channel and the receiving channel of the camshaft adjuster or the camshaft is formed in at least one rotational angle range, while the transfer cross section is closed in other rotational angle ranges.
- 2. Camshaft adjuster according to claim 1, wherein several of the supply channels or the receiving channels are formed, which are distributed uniformly or non-uniformly around a periphery.
- 3. Camshaft adjuster according to claim 1, wherein at least one non-return valve is arranged in the lubricant circuit.
- 4. Camshaft adjuster according to claim 1, wherein a lubricant injection nozzle is arranged downstream of the receiving channel.
- 20 5. Camshaft adjuster according to claim 1, wherein the gear drive is constructed as a wobble plate gear drive.
